METHOD AND APPARATUS FOR MAKING BUILDING PRODUCTS

Filed Sept. 14, 1926

UNITED STATES PATENT OFFICE.

THOMAS ROBINSON, OF NEW YORK, N. Y., ASSIGNOR TO LANCASTER ASPHALT, INC.

METHOD AND APPARATUS FOR MAKING BUILDING PRODUCTS.

Application filed September 14, 1926. Serial No. 135,327.

This invention relates to the manufacture of prepared building products suitable for roofing, siding, and other purposes, and has to do more particularly with a method and apparatus by which a building product of novel form can be produced cheaply and at a high rate of output. The improved product is particularly useful as a roofing to be used in place of ordinary wooden shingles or of prepared roofings for this purpose as heretofore constructed, but the utility of the product is by no means limited to this particular use, and it is of wide application for construction purposes.

Owing to the scarcity and high cost of wooden shingles and their lower fire resistance, such materials are being displaced rapidly by prepared roofings which are made in numerous ways. The product which is at present in widest use for the purpose is the so-called felt roofing which includes a base of felt made of rags, burlap, and the like, which is impregnated so as to render it waterproof by saturation with bituminous products, such as asphalt. The felt thus treated is then given a coating of asphalt which is of a higher melting point than that used as a saturant, so that the coating layer will readily withstand solar heat. Usually the surface of the roofing which is to be exposed to the weather is then covered with a layer of granular mineral material, such as crushed slate and the like, which gives the material a high fire resistance. This felt product, while in general satisfactory, is objectionable in that when it is used in the form of strip shingles which are laid in courses on the roof and have tabs which simulate the appearance of single shingles, these tabs in the course of time may have a tendency to warp and curl, thus giving the roof an unsightly appearance and in some cases making it leaky. Also the felt which is used as the main element in this product is relatively expensive.

The present invention is accordingly directed to the provision of an improved building material which is made by a continuous process so that there is produced a sheet of indefinite length which may be given a cross-section appropriate for the purpose to which the material is to be put, and this sheet is cut into units of appropriate size.

The plastic mass of which the new material is principally composed may be made of numerous materials, but I prefer to employ a plastic mass consisting of a binder and an aggregate. There are various binders suitable for the purpose, such as bituminous products of the type of asphalt, cements of different kinds, and the like, and the aggregate which I prefer to use may consist of crushed mineral matter, such as crushed slate, gravel, etc., or may consist of asbestos sand, fibrous asbestos, wood waste, such as sawdust, ground cork, and numerous other materials of this kind. This plastic mass is introduced by an extrusion operation into the jacket which is preformed. The jacket preferably consists of a flexible fibrous sheet, such as heavy paper, which may be impregnated so as to render it waterproof. This paper is preferably in the form of a web wound into a roll and prior to its winding on the roll, or just before it is moved to receive the plastic material, the web is folded lengthwise so as to form a generally V-shaped channel. This web is moved in the direction of its length past an extrusion mechanism by which the plastic material is introduced in the fold simultaneously from substantially the bottom thereof to the desired height, the web thus acting as a mold for the plastic material and also becoming a component part of the final product. The plastic filler is introduced into the web in a relatively fluent condition and preferably through extrusion orifices which deliver a plurality of rod-like masses of the plastic compound. These masses are discharged into the fold in the web and the latter is then moved through rolls which consolidate the several masses into a single core and also tend to shape the product. Beyond the first rolls the edges of the jacket are folded to cover the mass contained between the plies of the web, and then the web and its contents are given a final shaping treatment. Thereafter, various other operations may be performed on the moving web to complete the product, including the application of coating material and its cutting into pieces of desired lengths.

For a better understanding of the invention reference may be had to the accompanying drawings, in which

Fig. 1 is a view in elevation and partially in section of the apparatus by which the new product is produced.

Fig. 2 is a plan view of a portion of the apparatus illustrated in Fig. 1.

Figs. 3 and 4 are sectional views on the lines 3—3 and 4—4 of Fig. 1.

Figs. 5 and 6 are end views of the discharge end of the extrusion mechanism,

Fig. 7 is a view partially in section of a part of a modified form of extrusion device,

Fig. 8 is a plan view of a strip shingle made of the new product with the different layers broken away for purposes of illustration,

Fig. 9 is a transverse sectional view on the line 9—9 of Fig. 8.

Fig. 10 is a face view of a single shingle of somewhat modified construction, and

Fig. 11 is a sectional view on the line 11—11 of Fig. 10.

Referring to these drawings, the new product which is shown in Fig. 8 in the form of a strip shingle, is illustrated as consisting of a plastic core 20, here molded to tapered section. This core may be produced as previously mentioned of numerous materials, and preferably includes a plastic binder which has a tendency to become hard on setting, and an aggregate mixed with the binder. The binder may consist of numerous substances such as asphalt and the like, asphalt being the product I prefer to use because of its cheapness and ease of procurement, and also on account of the fact that it may be handled without difficulty. The solid material which is employed with the asphalt may consist of granular mineral products, such as crushed slate, crushed granite, and the like, or it may consist of asbestos sand, infusorial earth, wood cuttings, such as sawdust, or ground cork or asbestos. Asbestos sand, which is a commercial product consisting of fine asbestos mixed with some gangue, is highly desirable for the purpose. This plastic mixture serves as a core for the new material and it is encased within a jacket sheet 21 which preferably is made of a cheap paper which may or may not be impregnated to render it waterproof. After the core and its jacket are combined and given the proper shape, the jacket may be encased within a coating layer 22, which is preferably of a relatively high melting point asphalt. This completely seals the jacket and core, protecting them against the weather, and also serves as an adhesive by which a layer 23 of mineral material, such as crushed slate or the like, may be affixed to the element so as to give it the usual weather surface.

The new material is produced by the process presently to be described in the form of a web of indefinite length, and this web may be given the tapered section illustrated in

Fig. 9, or the opposite faces of the material may be substantially parallel, as desired. For the purpose of producing roofing products the material is preferably given the tapered section illustrated, the thick end of which serves as the butt or exposed end of the element when laid. The material may also be made in the form of the single shingle illustrated in Fig. 10, or in the form of the strip shingle shown in Fig. 8. The strip shingle has a length corresponding to three or more single shingles and is provided with cut-out notches 24 along the thick edge, these notches extending inwardly at right angles to the edge so as to define spaced tabs 25. When a plurality of such elements are laid on a roof in the usual manner in courses, with the elements of one course partially overlapping those of the course beneath, the rear ends of the notches are concealed and the roof appears to be made of a plurality of spaced single shingles. While the product is illustrated in that adaptation which is primarily useful for roofing purposes, it will be understood that it may be made in numerous other forms suitable for siding and the like.

In the production of the new material the process employed involves the formation of a jacket preferably by folding a web of jacket material lengthwise to provide a channel defined by two plies of the web, these plies extending generally vertically. The folded web is then moved longitudinally with a continuous movement and during such movement the filling material is introduced into the space between the plies of the web by an extrusion operation. The filled web is then formed to the desired shape and succeeding operations are performed on it while it continues in movement.

The apparatus employed for carrying out the process is illustrated in one form in Fig. 1. This apparatus includes extrusion mechanism generally designated 26, which consists of a hopper 27 having a central partition 28. At one side of this hopper is introduced the plastic material, as, for instance, at 29, while the solid substance which is to be mixed with the plastic compound is introduced in the pocket 30. At the lower end of the hopper and in communication therewith, is a casing 31 containing a shaft 32 mounted on suitable bearings in any convenient manner and connected to a suitable source of power, not shown. This shaft carries beater blades 33 beyond the end of the hopper and the plastic and solid compounds flowing into the casing are rapidly agitated by the action of the beater blades and then conveyed forwardly into the discharge end of the casing by means of a screw blade 34, also mounted on the shaft. The casing has a vertical discharge extension 35, which is of relatively small cross-section, its lower

end having a V-shaped section to conform generally to the angle between the two plies of the web into which the material is to be discharged.

5 The jacket, which consists of paper or the like, is in the form of a web which is folded lengthwise and in this double form wound about a drum 36 mounted on a vertical shaft 37. This double web is led from the drum 10 with the edges of the plies uppermost, the web being guided by means of vertical rollers 37. A central roller 38 mounted in any convenient manner lies between the plies so as to spread them apart and the 15 lower end of the discharge extension 35 lies just beyond the rollers 37 and 38 between the plies. This extension is provided with an inclined surface 39 forming a discharge nozzle having openings 40 and these openings 20 may be all of the same size, but spaced at varying distances, as illustrated in Fig. 5, or the openings may diminish in size from top to bottom, as illustrated in Fig. 6. The plastic mixture consisting of the binder and 25 the solid material is continuously forced through the discharge nozzle by the action of the screw conveyor, and there are thus delivered into the space between the plies of the web a plurality of rods of plastic 30 material, one above the other. The rate of discharge of the material into the web and the size of the rods delivered from the discharge orifices are properly proportioned so that the quantity of plastic material fed into 35 the web will be sufficient to provide a core of the section necessary in accordance with the type of material to be produced. This plastic compound is preferably discharged in a relatively fluent condition, so that the 40 several rods have a tendency to flow together.

Passing beyond the discharge nozzle, the web with the plastic mixture between its plies, is then led through forming or shaping rollers 41, which are on inclined vertical axes and act to consolidate the core and also to give the product the desired shape. These rollers may be mounted either on inclined axes, as illustrated, or else the rollers may 45 be on vertical axes, but with a pass of the proper shape between them formed by chan- 50 neling the faces of the rollers.

The amount of plastic material introduced into the mold formed by the web is such as 55 not to completely fill the web, the edges thereof extending beyond the core. These edges are to be wrapped around one end of the core, as illustrated at 42 and 43 (Fig. 9) and for this purpose a pair of rolls 44, 45, 60 are employed which act on the edges of the web, consecutively turning it in in the manner illustrated. Beyond the rolls 44 and 45 the jacket with the core is passed through a second pair of forming rolls 46 which shape

the material to its final form. Beyond 65 these rolls the web of material is moved through turning and guiding rolls 47, 48, which give the web a quarter turn so that from this point it proceeds in a horizontal position.

In the event that the strip shingle illustrated in Fig. 8 is to be produced, the next operation performed on the material is the formation of the cut-out notches, and this is done by means of upper and lower co- 75 acting cutters 49 which have cutting means excising narrow strips of the material from one edge thereof.

Beyond the cutting rolls the material is given a coating of water-resistant substance, 80 preferably a high melting point asphalt. This material is discharged upon the web by means of a nozzle 50 and the excess runs into a vat 51. Rollers 52 and 53, the lower roll 53 running in the material in the vat, 85 provide a means for applying the coating to the lower face of the web. At a point beyond the coating apparatus means are provided for applying the facing material which may be a granular substance, such as 90 slate, or the like. This apparatus is illustrated in conventional form as consisting of upper and lower rolls 54 and 55, with a hopper 56 by which the granular substance is distributed on the material to be embedded 95 by the action of the rolls. Beyond the rolls 54 and 55, the material passes through a cutting mechanism conventionally illustrated as consisting of a revolving shaft 57 with cutters 58 which strike the material and sever it into the desired lengths.

The apparatus is illustrated and above described somewhat conventionally, and it will be understood that the spacing of the different elements which act on the material 100 will be such as to permit the material to set so that it has the necessary mechanical strength to withstand the treatment which it undergoes. Also it will be noted that the extrusion mechanism is provided with a steam jacket 59 which may be necessary in some instances to heat the mixture and maintain it in the plastic condition, although asphalt in some forms may be extruded at a relatively low temperature.

Instead of folding the web lengthwise to form the jacket and then mounting this folded web on a drum from which it is led to the filling mechanism, the apparatus illustrated in Fig. 7 may be employed, in which the web 60 is mounted in flat form on a drum or spindle, being then led over a guiding roll 61 and between guide rolls 62 and 63. Small rollers 64 and 65 suitably mounted 115 press against the web along its central axis 120 and depress the web so as to give it the desired lengthwise folding. When the web is 125 folded to the desired shape by such rolls, it

passes the discharge nozzle of the extrusion mechanism and receives the core in the manner previously described.

While the product illustrated in Fig. 9 is suitable for numerous purposes, in some instances it may be desirable to make a product which, when laid with others in course, will give the roof the appearance of being covered with shingles or roofing elements of unusually heavy butt. For this purpose one ply of the web is folded upon itself to form a flap, as illustrated at 66 in Fig. 11. This folding of the web can be done either prior to the mounting of the web on the drum 37, or may be formed by appropriate folding means when the flat web is drawn off the drum, as illustrated in Fig. 7. By providing the flap along one ply of the web, the roofing product is given a transverse layer of increased thickness and this layer 67 is placed at that part of the element which is normally overlain by the elements of the course above. The butt edge of the elements in the upper course are placed in registry with the lower end of this band of increased thickness so that the butts of the elements of the upper course are thus raised considerably above the plane of that part of the face of the element designated 68. This gives the butts of the elements the appearance of being unusually thick, and increases their marketability.

The product produced by the new apparatus may be made in either light or heavy weights by a proper selection of the filler, as, for instance, when a heavy product is to be made the filler preferably used will contain sand or crushed mineral material, whereas when a light weight product is desired, the solid material may be ground cork, sawdust, asbestos, and the like.

The rolls which are employed for shaping and compressing the core may be steam heated if desired, so that the mass may be extruded at a relatively low temperature and then compacted by rolls which impart sufficient heat to the mass to render it fluent to the desired degree. When the mass is extruded in a somewhat plastic condition, the fluidity of the binder and the fact that the jacket is being moved along in a vertical position will result in a concentration of the solid material in the narrow end of the product. This increases the density of this part of the core and the product consequently has a substantially uniform rigidity because the thinner part of the core contains material of greater density than the thicker part. The same result follows when the solid material used in the core is lighter than the binder, for under these conditions the solid material will have a tendency to remain in suspension near the upper end of the product as it is being produced and the binder, which is heavy, will be concentrated

in the thinner or lower end. Here again the product has a density which varies from one end to the other, with the denser part of the core in the thinner end of the product, so that again the rigidity of the product is substantially uniform from one edge to the other. This result is assisted by the application of the shaping pressure for the channel between the plies of the product at the point where the material is introduced into it is considerably thicker than it is in the final form of the product. Accordingly, the shaping rolls exert a considerable pressure on the roller edge of the jacket, compacting and solidifying the plastic material within the jacket at this part of the core to a greater extent than that near the free edges of the web. This again results in a material which has a core of greater density along the thin edge than at the thick edge and the rigidity, being dependent on the density of the core, will be substantially the same from one end to the other, although the thickness of the core varies. Owing to this action of the roll in compacting the material, it is evident that the same result will be obtained, whether or not the material passes between the rolls in a horizontal or vertical position.

It will be apparent from the foregoing that the new process and apparatus permits the production of this building material at a rapid rate and at a low output cost because the process is a continuous one and need not be interrupted for any considerable periods of time. When one roll of the jacket is exhausted, another one will be placed in position and the end of one roll will be connected to the other so that the feeding is continuous. The introduction of the material by an extrusion operation permits the jacket to be completely filled and the material to be distributed in the jacket so that the shaping operations performed on the material thereafter are relatively simple. As here illustrated, the product is shown as being made of tapered section, but it is evident that by proper shaping of the rolls it is possible to produce the material in a relatively flat form, the opposite main faces of which are parallel. Likewise, the product may be made in a variety of forms of different widths and thicknesses, and it may be produced in the shape of flat rectangular sheets of different sizes, or in the form of roofing elements, as here illustrated.

The application of the granular surfacing material may be omitted from one or both faces, if desired, or the material may be applied to one face and a non-stick material, such as talc, may be applied to the other. The process which involves the production of a pre-shaped jacket which then receives a filling extruded into the jacket, with the jacket acting as a mold during the process of formation of the core, permits the product

to be made very cheaply and as the product contains no expensive elements, such as felt, it is evident that its cost for material is much lower than in the manufacture of the 5 present prepared roofings or other building products of this character. Furthermore, by the employment of the extrusion process for introducing the plastic material into the web or jacket simultaneously from substantially 10 the bottom thereof to the desired height, the handling of the core material in plastic condition is greatly facilitated, and a proper distribution of it is made possible. By proper selection of the extrusion nozzles 15 and the rate at which the extrusion mechanism is operated, the web may be filled with the plastic material in such amounts as are required and this material may be distributed evenly or in rods of varying sizes 20 which are suitable for filling a web of tapering cross section.

I claim:

1. Apparatus for making building products and the like which comprises means for maintaining a folded web in motion, an extrusion device operable to introduce a plastic mass into the space between the plies of the web simultaneously from substantially the bottom thereof to the desired height, pressure means for shaping the web containing the plastic mass, and a cutter operable to cut the filled web into selected lengths. 25

2. A method of making building material, which comprises moving a longitudinally folded sheet lengthwise, simultaneously extruding a filling material into the fold from substantially the bottom thereof to the desired height, applying pressure on the filling material within the fold to compact it, and cutting the filled web into selected lengths. 30 35 40

In testimony whereof I affix my signature.
THOMAS ROBINSON.
